Primary Examiner—Stella Reid

[57] CLAIM

The ornamental design for a back massager, as shown and described.

DESCRIPTION

FIG. 1 is a front elevational view of a back massager showing my new design;

FIG. 2 is a rear elevational view thereof;

FIG. 3 is a top plan view thereof, the opposite side being a mirror image;

FIG. 4 is a left side elevational view thereof;

FIG. 5 is a right side elevational view thereof; and,

FIG. 6 is a perspective view thereof.
